UNITED STATES PATENT OFFICE.

MATHEW BLACK AND SAMUEL OLKIN, OF BROOKLYN, NEW YORK.

GARMENT-SUPPORTING CLAMP OR CLASP.

Application filed March 14, 1925. Serial No. 15,461.

To all whom it may concern:

Be it known that we, MATHEW BLACK and SAMUEL OLKIN, both citizens of the United States of America, residing both at Brooklyn, Kings County, and State of New York, have invented certain new and useful Improvements in Garment-Supporting Clamps or Clasps, of which the following is a specification.

10 This invention relates to garment supporting clamps or clasps and in particular to one adapted for attaching together a trousers and shirt, whereby the shirt will be held down and the trousers will be supported without the use of suspenders or belt.

While it is to be understood that the clasp can be used in any position to hold any material together, we prefer to show 20 it in combination with a pair of trousers and shirt, and one of the important objects of the invention is to provide a clasp which will not tear the clothing and which will hold the same together securely.

25 A further object is to provide a clamp or clasp which will hold a shirt and trousers together, the shirt being held frictionally so that it will not tear or rip.

30 A further object of the invention is to provide a neat compact clasp having few parts, which will not, while in use be felt by the wearer and one which may be quickly adjusted to fasten or release the clothing parts or material held together.

35 Referring to the drawing wherein we have shown a preferred embodiment of our invention:—

Figure 1 is an enlarged view in elevation of my clasp the same being shown attached to a trousers and holding a portion 40 of a shirt therein.

Figure 2 is an enlarged side view of the clasp as seen in Figure 1.

45 Figure 3 is an enlarged section taken on the line 3—3 of Figure 1 showing the arrangement of the gripping rollers and the releasing bar,

50 Figure 4 is an enlarged section taken on the line 4—4 of Figure 1 showing the arrangement of the slots in each piece of the clasp member, and

55 Figure 5 is an enlarged side view of the clasp, the parts thereof being shown in open or releasing position.

55 Referring to the drawing in detail 5 indicates the top edge of a pair of trousers

or other garment and 6 a portion of a shirt or other garment both of which are adapted to be held together by the clasp which consists of two base members 7 and 8 the member 7 having the side wings or flanges 9 shaped to provide in their upper portions bracket like projections 10 between which are carried a stationary roller 11, the lower portions of the flanges 9 being formed to provide extensions 12 in which are cut the slots 13, there being disposed in said slots the ends of a lock bar 14 which has sliding movement in said slots. The lock bar carries at its center portion and fixed thereto, a latch member 15 the head of which is rounded and flattened as at 16 the purpose of which will be hereinafter brought out. The latch 15 is provided with a depending portion 17 which is curved slightly and extends below the edge of the base member 17 to form a finger piece 18.

The base member 8 is provided at its side edges with flanges 19 the upper portions of which are extended as at 20 to provide journals for the ends of a roller carrying shaft 21, the roller 22 carried thereby being revolvably mounted. This roller 22 and the roller 11 may be made of hard rubber or other suitable material which will not rust or mark the material held therebetween. The peripheries of the rollers as shown may be fluted longitudinally of their length as at 23, but this fluting may be dispensed with if desired. It gives the rollers a better grip on the material and as roller 22 is revolvably mounted, the goods held between the rollers is locked in the grooves or flutes.

The lower portion of the wings or flanges 19 of base member 8 are cut to provide hooks 24, the outer edges of which are curved as at 25 to provide a cam surface, and the inner sides of which provide receptacles which match the slots 13 cut in the extensions 12 before referred to, and in which the lock bar 14 is adapted to seat. The lower edges of the flanges 19 and 9 on the base members 8 and 7 respectively are pivotally held together by the pins or rivets 25^a and the flanges 19 on base 8 fit snugly within the flanges 9 of base member 7.

As shown in Figure 5 the parts 7 and 8 are swung open or in position to release the goods. In Figure 2 they are shown in locking position. The base member 8 is provided with ears 26 at each corner thereof, which are provided with openings to

allow the clasp to be sewn to the trousers or other garment.

In the operation of the clasp in use for holding a trousers and shirt together, we take a fold 27 of the shirt material and insert it as shown in Figure 5 in position between the rollers to be gripped thereby when the clasp is closed, it being understood that the roller 22 which revolves is disposed below and against roller 11 when the clasp is closed, and the fold 27 of the shirt is gripped securely between the rollers. When the clasp is open the lock bar 14 normally rests in the bottom of the slots 13, but when the member 7 is moved towards member 8 to close the clasp, the cam like edges 25 of the hooks 24 on member 8 raise the lock bar 14 and it rides over the top edge of the hook and drops into the inside of the hooks, as the clasp is vertically disposed and the weight of the lock bar, will cause it to fall by gravity into position within the hook to lock the two parts 7 and 8 together. Simultaneously with the raising of the lock bar, the rollers come into contact to engage the goods to be held and the flutes of the rollers cause the same to snap into locking position, the actual locking being carried out by the lock bar 14, as described. In this position, the shirt and trousers will be firmly secured together and without danger of damage to the relatively thinner material of the shirt. The rollers being made of rubber or other suitable material will compensate for various thicknesses of material held therebetween.

When it is desired to release the material held in the clasp, the finger piece 18 of the latch 15 which is secured to the locking bar 14 is pushed upwardly to move the lock bar out of engagement with the hooks 24 at which time the clasp parts can be swung open on their pivots 25 to separate the rollers and release the material held therein. The enlarged head 16 of the latch 15 is provided for the purpose of preventing the same from getting into the flutes of the lower roller and thus prevent its rotation to release the material when members 7 and 8 are opened. A lip 28 is provided in member 8 through an opening in which the depending portion

of latch 15 passes. This lip retains the locking bar in position.

It is evident that we have provided a clasp having few parts and one which may be disposed at spaced points around the interior edge of a pair of trousers or a skirt which will not only be concealed but will securely hold a shirt or waist so that the use of a belt, suspenders, buttons or other sustaining medium are dispensed with. Also we have provided a clasp which will not be felt by the wearer and one which can be adjusted with a minimum of time and effort and which will not mar or tear the material held therein.

Having described our invention what we claim is:—

1. A garment clasp comprising members pivoted together and adapted to be opened and closed, a fluted roller in each of said members, the rollers being adapted, when the members are closed, to hold material therebetween, a locking bar in one of said members, hook portions on the other member into which the locking bar is adapted to fit to lock the members together, one side of said hook portions serving as a cam to operate said locking bar, and a finger latch for disengaging the locking bar from said hook portions.

2. A garment clasp comprising a member adapted to be sewn to a garment, a roller revolvably carried in said member, another member pivoted to said first member, a stationary roller therein adapted to contact with said revolvable roller to hold the material of an adjacent garment therebetween when the members are closed, slots in said second member, a locking bar in said slots, hook members, the edges of which constitute cams whereby when the members are closed, the edges of said hook members raise the locking bar automatically to allow it to subsequently fall within the hook members to lock the clasp members together, and a finger operated latch associated with the lock bar to release said clasp members so that the same may be opened and the material between the rollers released.

MATHEW BLACK,
SAMUEL OLKIN,
